(57) **CLAIM**

The ornamental design for a one piece baby garment with a zipper inseam, as shown and described.

DESCRIPTION

FIG. 1 is a bottom perspective view of a one piece baby garment with a zipper inseam;

FIG. 2 is a front plan view of the one piece baby garment with a zipper inseam of FIG. 1;

FIG. 3 is a back plan view of the one piece baby garment with a zipper inseam of FIG. 1;

FIG. 4 is a left side elevation view of the one piece baby garment with a zipper inseam of FIG. 1;

FIG. 5 is a right side elevation view of the one piece baby garment with a zipper inseam of FIG. 1;

FIG. 6 is a top plan view of the one piece baby garment with a zipper inseam of FIG. 1;

FIG. 7 is a bottom plan view of the one piece baby garment with a zipper inseam of FIG. 1; and,

FIG. 8 is a bottom perspective view of the one piece baby garment with a zipper inseam of FIG. 1 shown in an open position.

The broken lines shown in the drawings illustrate portions of the one piece baby garment with a zipper inseam that form no part of the claim.

1 Claim, 6 Drawing Sheets
